United States Patent Office

Des. 207,528
Patented May 2, 1967

207,528

PULL

La Verne E. Clayton, Rockford, Ill., assignor to Amerock
Corporation, Rockford, Ill., a corporation of Illinois

Filed July 11, 1966, Ser. No. 3,010

Term of patent 14 years

(Cl. D10—8)

FIGURE 1 is a front view of a pull incorporating my new design.

FIG. 2 is a top view of the pull.

FIG. 3 is an enlarged sectional view taken along the line 3—3 in FIG. 1.

FIG. 4 is an enlarged sectional view taken along the line 4—4 in FIG. 1.

FIG. 5 is an enlarged sectional view taken along the line 5—5 in FIG. 1.

FIG. 6 is an enlarged fragmentary sectional view taken along the line 6—6 in FIG. 3.

I claim:

The ornamental design for a pull, as shown.
